SOUND-REPRODUCING SYSTEM

Application filed July 30, 1928. Serial No. 298,298.

This invention relates to sound reproduction, and especially to reproduction from photographic records.

Such records are now well known. In one form, for example, the record is produced on a film, the density (or degree of translucency) is longitudinally variable in accordance with the sound to be reproduced. Now if such a record be passed between a steady source of light and a photo-electric device, this device can control the current in a circuit, and the resultant current variations can be caused to operate a device that translates current variations into sound; such for example as the now commonly used loud speakers. Since such reproducing systems as just outlined are now in quite general use, and especially in connection with "talking movies", it is considered unnecessary to detail them further.

My invention is in the nature of an improvement over a system of this character; and accordingly it is one of the objects of my invention to improve the reproduction of sound by this means.

It is obvious that in a record of this character (the so-called "variable density" record), the record carrying medium should, for perfect results, have its density continuously and accurately variable along its length; in other words, for each increment of length there must be a corresponding increment or decrement of density. Practical considerations immediately show that the length increments cannot be reduced to a mathematical infinitesimal, such as are treated for example in differential calculus; and consequently, this theoretical perfection is lost.

Nevertheless, the human ear being itself incapable of discriminating between perfection and near perfection, highly satisfactory results can be obtained when the density variations occur in widths of say of the order of one or two thousandths of an inch where the rectilinear speed of the record is approximately fifteen inches per second at any given point. Consequently when such a density record is viewed with the naked eyes, it appears as a series of very closely spaced bars of varying widths and of varying darkness or density. These bars are the result of passing the

light that produces the record through a correspondingly narrow slit or "iris" onto the record which is later photographically developed.

For reproduction purposes, the density of each individual bar should theoretically be caused to affect in succession, the photo-electric device, so that the device may faithfully follow the density variations of the whole record. In order to accomplish this result, it has been customary to provide a narrow slit or iris across which the record is passed. However, it was found that dirt or other foreign matter soon clogged up at least a portion of the opening, and interfered with the transmission of light therethrough. Even if the reproduction were not entirely lost, yet due to the irregular blurring of the optical path occasioned by the foreign matter, a serious distortion would result. Consequently it has been proposed to fill the slot with a transparent plug, such as a crystal or glass, that would effectively keep out the foreign matter.

Such an arrangement is nevertheless far from ideal. The film, travelling in contact with the iris, is rubbed thereby and a scratching of the record is caused by fine dust or particles trapped between the film and the slot. It is another object of my invention to obviate all these disadvantages and yet secure the highly desirable accurate reproduction.

I accomplish this result by passing the light through an iris that is comparatively wide; of the order of an eighth of an inch, and by maintaining the film record entirely out of contact with the structure in which the opening is provided. The image of a large number of striations or density lines is then projected in magnified form onto a baffle, which has a slot or an elongated transparent window just wide enough to pass only a very small fraction of a single striation onto the photo-electric device. Since the image is optically projected and fractionated by a slot or light passage remote from the film, the slot can be kept easily free of interfering foreign matter, and may be provided with a transparent covering, such as a glass plate or plates on both sides thereby insuring a clear light path at all times.

The advantages of such an optical system are important. In prior devices, the photo-electric device was subjected at frequent points on the record to the light intensity produced by a small group of density lines, known as harmonic groups, the combined or total width of which was much smaller than the width of the fractionating slot; and accordingly, attempts to record and reproduce variations in tone volume could not be readily accomplished, for the individual density variations were lost. In my scheme the tone volume can readily be recorded and reproduced, for a very much finer subdivision of the lines is provided, and the density variations, which occur over the entire width of the individual lines being the volume factor, can be reproduced by making the magnification sufficiently large, and the opening or window in the baffle plate sufficient narrow, so as to scan across the width of the line from one edge to the other. Such scanning is practically impossible where a slot having a width of .001 of an inch is directly employed to fractionate fundamental tone lines more or less of that width, and harmonic lines are present possibly as narrow as .0005 or even .0002 of an inch, which condition now obtains in other devices for reproducing sound.

My invention possesses many other advantages, and has other objects which may be made more easily apparent from a consideration of one embodiment of my invention. For this purpose I have shown a form in the drawings accompanying and forming part of the present specification. I shall now proceed to describe this form in detail, which illustrates the general principles of my invention, but it is to be understood that this detailed description is not to be taken in a limiting sense, since the scope of my invention is best defined by the appended claim.

Referring to the drawings:

Figure 1 is a diagrammatic view of a reproducing system incorporating my invention; the optical system and its associated structure being shown mainly in section.

Fig. 2 is a side elevation of the optical system and its associated structure, some of the parts being broken away to illustrate the structure more clearly.

Fig. 3 is a plan view thereof; and

Fig. 4 is a diagram of a portion of the magnified image with the baffle plate.

Fig. 5 is a magnified view of an individual tone line or photograph showing the density variation, or graduation over its entire width, characteristic of the volume factor.

The record film 11 in this instance is shown as carrying not only the sound record 12, but also the frames 13 of a motion picture for the purpose of producing talking pictures. This film has a series of sprocket 65 tooth engaging apertures 14 near each edge;

in the present instance, only the apertures at the right hand edge (Fig. 3) are engaged by a sprocket wheel 15. This wheel as most clearly shown in Fig. 1, can be used as a driven wheel, as by the provision of a drive shaft 16. Optionally one or the other sprocket wheels 17 (Fig. 2) can be used as a driver; otherwise it can serve, as sprocket 18, merely as a tensioning idler. Other idlers, such as 19, 20, 21, can be used to maintain the film 11 in proper arcuate configuration with respect to wheel 15.

Wheel 15, as shown in Fig. 2, is provided with an undercut flange 22 that is of considerably less width than film 11, so that the free edge of the film projects beyond the narrow rim 23 and is supported thereon. The film 11 is urged sidewise to maintain it in correct position with relation to the optical system, as by a ring 24, urged resiliently as by a series of springs 25, against that edge of the film which is nearest the sprocket wheel. To adjust the spring pressure, an adjustable ring 26 is used, against which the springs 25 abut, and which is adjustable by having it threaded onto the screw threads 27 shown as formed as an extension of wheel 15. Wheel 15 has sufficient weight to produce a fly-wheel effect, and to maintain the speed thereof substantially uniform. This uniformity is quite essential for accurate reproduction.

That part of film 11 which projects beyond rim 23 carries the sound record. The optical system whereby light shines through the record will now be described. A stationary support 28 is used, that has an offset portion 29 extending beneath flange 23. This portion has an arcuate segment 30 in which is formed a comparatively wide slot 31 to permit light to shine through the projecting edge of film 11 as it travels past. This slot, as shown in Fig. 2, can be stepped in order to prevent diffraction at the inner edge; and it is furthermore so wide as to preclude the possibility of it clogging. In fact, glass windows can readily be placed on each end of the slot if necessary.

As shown most clearly in Fig. 1, the film 11 is spaced from the slot opening, so that it cannot be scratched or injured by the slot edges. Light can be passed through the slot in any desired manner; for example, an incandescent lamp 32, appropriately supported adjacent support 28, can be used. A lens 33 concentrates the light onto a prism reflector 34 supported in the offset portion 29 of support 28. Lens 35 in this offset portion then concentrates the rays to pass it through aperture or slot 31. After the light passes through film 11, the image of the record thereon is magnified by any desired arrangement, as by lens 36, and the magnified image is projected onto a baffle plate 37.

As shown most clearly in Fig. 1, the image of the record covering slot 31 at any instant

is spread between the divergent lines 38, 39. However, only a very small portion of this image is allowed to affect the light sensitive device 40, such as a photo-electric cell. For this purpose, baffle 37 has a central slot 41, or window wide enough to pass only such rays as correspond to a portion only of a density line. These rays can then be again diverged to affect the electron emitting electrode 42. 10 This device can then be used to affect, in a well known manner, one or more stages of electronic emission amplifiers such as 43, and finally the amplified electrical impulses can pass to a loud speaker 44 or equivalent device 15 that translates these impulses into sound waves.

The baffle plate 37 is shown as having an exaggerated slot opening 44. As a matter of fact, the slot is made very narrow, as indicated by the line 45 in Fig. 4, so that it serves to fractionate or "scan" the individual bars. In this way, the variations in volume of the sounds originally recorded can be faithfully reproduced.

25 The slot in baffle plate 37 may be equipped with transparent windows, such as a sheet of glass or mica, cemented on either or both sides of the baffle as shown at 37a, thereby preventing the accumulation of dirt or foreign 30 matter in the light passage, or the baffle plate may be made of a transparent solid such as glass or quartz coated or covered on one face with an opaque substance, that is heavily silvered or painted and a very narrow line 35 ruled through the covering to the glass surface thereby permitting light to pass, as if it were an open slot. This arrangement permits easy cleaning when, if ever, any dirt should accidentally accumulate at that point. 40 In view of the fact that the baffle plate is remote from the accumulated dirt adhering to the film, this elementary trouble is entirely overcome.

I claim:

45 In a structure defining a slot for photographic sound records, a wheel over which the record can be placed, said wheel having a flange beyond which the record can project, a stationary support having a part projecting 50 beneath said record, and forming with the wheel an opening over which the record travels, a lens structure arranged to pass radiations radially through the opening, and supported on said part, and a reflector also supported thereon, for directing radiations from 55 a source through the lens.

In testimony whereof I have hereunto set my hand.

DELMAR A. WHITSON.
